J. S. Wedder, of Troy, N.Y.
Assoc to
Wolfe & Warren, of Troy, N.Y.
Letters Patent No. 867 Dated Jan'y. 27th 1857.

The Schedule referred to in these Letters Patent and making part of the same.

To all whom it may concern.

Be it known that J. S. Wedder of Troy, County of Rensselaer and State of New York, have invented or produced a new and original design for a parlor cook stove which I call the "Union" and I hereby declare that the following is a full and exact description of the same, reference being had to the annexed perspective drawing of the stove, forming a part of this specification.

The description of my parlor cook stove design is as follows, A, is the ornamental top, composed of scrolls (a.a), and bars (b.b), and scolloped border (c), B is the fixed top.

Des. 807

with the ornamental moulding (d). C. is the front plate with the leaves (e.e) rope arch (f) and side ornaments (g). D is the hearth plate, with ornamental ends (h). E is the blower composed of bars (i.i) and leaves (j). F is the oven door, the panel of which is decorated with the ornament (k) and leaves (l.l). G. is the end plate, with fire door H, decorated with ornament (m), the lower part of the plate is decorated with the ornamental work (n) and (o.o). I is the bottom plate with the shell work hearth (p) leaves (q), corner shells (r.r) & moulding (s). T is the leg with the ornament (t) upon its face.

Having described my design for a parlor cook stove, what I claim as new, and desire to secure by Letters Patent is,

The ornamental design and configuration of parlor cook stove plates such as herein described and shown in the annexed drawing.

Witnesses.

J. J. Savage.

John Moran

N. S. Wedder.
